UNITED STATES PATENT OFFICE.

JOHN J. TATUM, OF BALTIMORE, MARYLAND, ASSIGNOR OF ONE-HALF TO
ALOIS P. PRENDERGAST, OF BALTIMORE, MARYLAND.

BRAKE-SHOE.

No. 856,188.

Specification of Letters Patent.

Patented June 4, 1907.

Application filed September 11, 1906. Serial No. 334,152.

To all whom it may concern:

Be it known that I, JOHN J. TATUM, of Baltimore, Maryland, have invented a new and useful Improvement in Brake-Shoes, which improvement is fully set forth in the following specification.

The present invention relates to brake-shoes, and particularly to such brake-shoes as are adapted to receive and have attached thereto partially worn shoes, to the end that the partially worn shoes may be completely used up instead of being thrown on the scrap heap.

Means have heretofore been proposed for securing partially worn transversely-divided shoes to the face of other shoes, and means have also been suggested for securing partially worn continuous shoes to the face of shoes of the same type. The practical objection among others to the first class is that the means employed can only be used with transversely-divided shoes; and to the second class, that the means for securing the shoes together consist of flexible or malleable pins, and, in one instance the shoe is either weakened at the point where it is secured to the brake-head by unduly enlarging the locking recess, or, in another instance, the locking pin, by extending into the locking recess in the face of the shoe, prevents shoes from being closely and compactly piled together in shipping the same.

The object of the present invention is to provide a cheap and strong brake-shoe which may be quickly and effectively locked to the face of another shoe—and, if desired, removed therefrom—to the end that the same is less liable to be broken in handling and use, and so securely fixed to the associated shoe as to render any accidental separation practically impossible.

The invention is illustrated in the accompanying drawings, wherein—

Figure 1 is an elevational view, partly in section, illustrating a partially worn brake-shoe secured to the wearing face of another shoe which latter is secured to the brake-head; Fig. 2 is a rear elevation of two shoes secured together; Fig. 3 is a transverse sectional view on the line a—a, Fig. 2; and Fig. 4 is a view of the key employed to lock the shoes together.

In said drawings, 1 is a brake-shoe having attaching lug 2 provided with opening 3 by which the shoe is adapted to be secured to the brake-head 4 by key 5, as usual; and 1' indicates a partially worn shoe secured to the wearing face of said first-mentioned shoe. Guiding lugs 6 are formed on the rear of the shoes, and guiding recesses 7 are provided in the wearing face of the shoe for the reception of said lugs 6. Attaching recess 8 is formed in the wearing face of the brake-shoe, in which recess attaching lug 2 is adapted to be inserted when it is desired to secure a partially-worn, or other, shoe to the wearing face of the shoe fastened to the brake-head.

Extending through the body of the shoe, and having openings in the rear face thereof, is a channel or keyway 9. This channel or keyway intercepts recess 8 and when the attaching lug 2 of a partially worn shoe is inserted into the recess 8, opening 3 therein is in alignment with said channel or keyway. To therefore fixedly secure the two shoes together, it is only necessary to introduce a key 10 into said channel or keyway, which key passes also through the opening 3 in the lug of the partially worn shoe, thus firmly keying together the two shoes. In order to preclude any possibility of the key being accidentally jarred or shaken out of its keyway, the latter is provided, preferably at each end thereof, with a land or straight portion 11 arranged at an angle to the curve of the keyway. When, now, a key has been introduced to secure two shoes together, it is only necessary to hammer the ends of the key into contact with said straight portion 11 to prevent any accidental displacement of the same. The removal of the key may be readily effected by prying up the ends of the same with a chisel, and then simply pulling the key out.

What is claimed is:

1. A brake-shoe provided in its wearing face with recesses adapted to receive the attaching and guide lugs upon the back of another shoe, and a locking means at the rear of said first-mentioned shoe for securing the latter thereto.

2. A brake-shoe provided in its wearing face with recesses adapted to receive the attaching and guide lugs upon the back of an-

- other shoe, and a key passing through the body of said first-mentioned shoe for securing the latter thereto.
3. A brake-shoe provided in its wearing face with recesses adapted to receive the attaching and guide lugs upon the back of another shoe, and a key passing into the rear face of said first-mentioned shoe for securing the latter thereto.
- 10 4. A brake-shoe provided in its wearing face with recesses adapted to receive the attaching and guide lugs upon the back of another shoe and provided with a channel or keyway opening from the back of the shoe and a key adapted to engage in said channel or keyway to secure the two shoes together.
- 15 5. A brake-shoe provided in its wearing face with recesses adapted to receive the attaching and guide lugs upon the back of another shoe and provided with a channel or keyway opening from the back of the shoe
- 20
- and intercepting said attaching recess, and a key adapted to pass through said keyway and through the lug in said attaching recess.
6. A brake-shoe provided in its wearing face with recesses adapted to receive the attaching and guide lugs upon the back of another shoe and provided with a channel or keyway intercepting said attaching recess and having openings in the rear-face of the shoe, and a key adapted to pass through said keyway and through the lug in said attaching recess, the ends of said key being adapted to be bent into contact with a land or straight part arranged in said keyway.
- 35
- In testimony whereof I have signed this specification in the presence of two subscribing witnesses.

JOHN J. TATUM.
